UNITED STATES PATENT OFFICE

WILLIAM HINES, OF WASHINGTON, DISTRICT OF COLUMBIA

ERASER

Application filed May 8, 1929. Serial No. 361,428.

(GRANTED UNDER THE ACT OF MARCH 3, 1883, AS AMENDED APRIL 30, 1928; 370 O. G. 757)

This invention described herein may be manufactured and used by or for the Government for Governmental purposes, without the payment to me of any royalty thereon.

6 This invention relates generically to erasers more especially to those of the annular type commonly referred to as typewriter erasers.

One object of this invention is to provide 10 an eraser formed entirely of rubber and having facilities for producing an air blast to remove erased particles or effect separation of the sheets of carbon or typewriting paper, thus avoiding smudging of the fingers and 15 loss of time as now occurs in producing multiple carbon copies where the sheets must be continually separated.

Another object of this invention is to provide 20 an eraser of the annular type constructed entirely of rubber and embodying suction devices through the instrumentality of which the eraser may be quickly and conveniently affixed to a flat surface as for instance the face of a typewriter so that when its usage 25 is required it may be readily located.

Another object of this invention is to produce 30 an eraser embodying a rubber body portion circumscribed by an annulus of rubber, the latter having less flexibility than the body portion and constituting a key adapted to seat in a suitable key-way formed in the circular strip of erasing material surrounding the body portion whereby the eraser material 35 to be easily and conveniently replaced when occasion demands.

Another object of this invention is to effect 40 a typewriter eraser of the annular type having a body portion formed of flexible hemispherical shaped sections peripherally united by a strip of rubber having less flexibility than that of the side walls of the body portion to form a key adapted to seat in a key-way formed in the strip of eraser material 45 encircling the peripheral edges of the side sections of the body portion.

Another object of this invention is to provide 50 an all rubber eraser comprising cup-shaped side walls peripherally united and surrounded at the point of union with an eraser material, the respective side walls of

the body portion having flexible suction elements integral therewith to enable the eraser to be securely affixed to any flat surface.

Another object of this invention is to provide 55 an all rubber typewriter eraser having a body portion or cup-shaped flexible material peripherally united to provide a blast producing chamber, the latter having an outlet nozzle communicating with the exterior of the body portion, the nozzle being adapted 60 to extend through the annular strip of erasure material which surrounds the body portion and to function as an anchoring means for said material.

With these and other objects in view this 65 invention consists in certain novel details of construction, combination and arrangement of parts to be more particularly hereinafter set forth and claimed.

Briefly stated, this invention comprises a 70 body portion formed of a pair of cup-shaped side members united at their periphery to provide an air chamber, a nozzle communicating with the air chamber and extending to the exterior of the body portion whereupon 75 compression of the cup-shaped members will produce an air blast, a rubber annulus surrounding the body portion at the point of union of the side members, said annulus constituting a key adapted to fit into a key-way 80 formed in the strip of eraser material circumscribing the body portion, said material having an opening for the passage of the nozzle which latter serves not only as an outlet for the air in the chamber of the body portion, 85 but also as an anchoring means for the eraser material and a pair of suction cups integrally formed with the side members of the body portion.

Referring more particularly to the accompanying drawings in which corresponding parts are indicated by similar reference characters:

Fig. 1 is a side elevation of the eraser forming the subject matter of this invention, 95

Fig. 2 is a longitudinal section through the central portion of the eraser, and

Fig. 3 is a transverse vertical section taken on the line 3-3 of Fig. 1.

With the typewriter erasers at present 100

available the construction does not permit replacement of the eraser material when worn. Moreover, the brush with which such erasers are usually equipped will not function to remove the erased particles as completely as would an air blast and furthermore they are frequently misplaced with consequent loss of time in locating them. For this reason it is the aim and purpose of this invention to provide a simple, inexpensive all rubber eraser permitting ready removal and replacement of the eraser material, affording a blast producing means for quickly separating the sheets of carbon and typewriting paper and for removing the erased particles and finally having facilities by which the eraser may be affixed to the face of the typewriter so as to be always handy and in plain view of its operator.

20. In the illustrated embodiment characterizing this invention, there is shown a typewriter eraser of the character designated comprising a body portion (a) including hemispherically shaped sections (1) and (2) united at their periphery as at (3) to form an air chamber (4). The side sections (1) and (2) are of rather flexible rubber so as to be readily compressed to expel the air from chamber (4) through an outlet hereinafter to be referred to.

35. Integral with the sections (1) and (2) are a pair of suction cups (5) and (6) which enables either side of the body portion to be rigidly affixed to any flat surface as will be readily understood without further discussion.

40. The united peripheral edges of the side sections (1) and (2) are surrounded with an annular strip of rubber (7) of sufficient rigidity to form a key adapted to fit in a key-way (8), formed in the strip of eraser material (9) encircling the body portion, as clearly shown in Figs. 1 and 3 of the drawings.

45. The eraser material (9) is formed with a tapered opening (10) through which there projects a correspondingly tapered outlet nozzle (11) which establishes communication between the interior of the chamber (4) and the exterior of the eraser.

50. Manifestly nozzle (11) not only functions as an outlet for the air in chamber (4) of the eraser but also serves as an anchoring means for the eraser material (9) to prevent it creeping around the key.

55. Having set forth the structural details of this invention, it will be evident, compression of the side sections (1) and (2) of the body portion will produce a blast through the nozzle (11) of sufficient strength to completely remove all erased particles or effect separation of adhering carbon or typewriting sheets and that by virtue of the suction cups (5) and (6) the body portion of the eraser may be attached at either side to any flat surface as for instance the face of the typewriter so that

the eraser may be always maintained conveniently at hand and within sight of the operator.

70. Although in the foregoing certain elements have been described as best adapted to perform the functions allotted them, nevertheless it is to be understood that various minor changes may be resorted to within the scope of the appended claims without departing from or sacrificing any of the principles of the invention.

75. Having described my invention, what I claim as new and wish to secure by Letters Patent is:

80. 1. An eraser composed entirely of rubber and comprising a body portion formed of side sections, laterally spaced and united at their edges to form an air chamber, a rubber rib of less flexibility than the side sections and encircling the latter at their point of union, said rib constituting a key, a rubber strip surrounding and formed with a key-way to receive said key, said strip having an opening and a nozzle extending from the body portion through said opening to establish communication between the interior of said air chamber and the exterior of the eraser.

85. 2. An eraser composed entirely of rubber and comprising a body portion formed of cup-shaped side sections united at their edges and forming an air chamber, a rubber key encircling the body portion at the point of union of said side section, said key having less flexibility than the side sections, a strip of eraser material surrounding the key and formed with a key-way to provide a seat for

90. said key, a nozzle projecting from the body portion and extending into an opening formed in the eraser material to establish communication between said air chamber and the exterior of the eraser.

95. 3. An annular eraser composed entirely of rubber and comprising a body portion formed of cup-shaped side sections united at their periphery to provide an air chamber, a rubber key encircling the body portion at the peripheral edges of said side section, said key having less flexibility than the side sections, suction cups integrally formed with the side

100. sections, a strip of eraser material embracing the key and formed with a key-way to seat said key, a nozzle projecting from the body portion and through an opening in the eraser material to establish communication between the air chamber and the exterior of the eraser and to form an anchoring means for the eraser material.

105. 4. An annular eraser composed entirely of rubber and comprising cup-shaped side sections united at their peripheries, a rubber key encircling the body portion at the peripheral edges of said side sections and having less flexibility than the side sections, suction cups integrally formed with the respective side sections, a strip of eraser material cir-

cumscribing the key and formed with a key-way for its reception and a tapered nozzle extending from the body portion to a similarly shaped opening in the eraser material

5 to establish communication between the air chamber and the exterior of the eraser and to provide an anchoring means for the eraser material.

10 5. In an eraser a body portion composed of flexible material and incorporating an air chamber therein, erasing material encircling the body portion, an opening into the air chamber and a second opening in the erasing material communicating with the first opening for the purpose described.

15 6. An eraser comprising a body portion composed of flexible cup shaped side sections united at their peripheries to form an air chamber, an opening into the air chamber at 20 the junction of the peripheries, an annular strip of erasing material encircling the body portion and bestriding said junction, said strip being formed with an opening communicating with the first mentioned opening for 25 the purpose disclosed.

20 7. An eraser comprising a flexible body portion composed of cup shaped side sections united at their edges in the form of a rib, an air chamber in the body portion, a passage 25 through the rib into the air chamber, an annular strip of erasing material encircling the body portion and bestriding the rib, said strip being formed with a passage communicating with the first mentioned passage.
